Des. 230,180

Patented Jan. 29, 1974

230,180

JEWELRY FINDING

Maurice Silber, 183—07 69th Ave.,
Fresh Meadows, N.Y. 11365

Filed Feb. 28, 1972, Ser. No. 230,210

Term of patent 14 years

Int. Cl. D11—01

U.S. Cl. D45—19 R

FIG. 1

FIG. 4

FIG. 2

FIG. 3

FIG. 5

FIG. 1 is a top plan view of a jewelry finding illustrating my new design;

FIG. 2 is a front elevation thereof;

FIG. 3 is a right side elevation thereof;

FIG. 4 is a left side elevation thereof; and

FIG. 5 is a bottom plan thereof.

I claim:

The ornamental design for a jewelry finding, as shown.
